UNITED STATES PATENT OFFICE.

JOHN H. SPANGLER, OF BEMIDJI, MINNESOTA, ASSIGNOR TO NATHANIEL ASA ADDISS,
OF MINNEAPOLIS, MINNESOTA.

COLLAPSIBLE BOX FOR SHIPMENT OF EGGS AND OTHER ARTICLES.

Application filed August 8, 1921. Serial No. 490,496.

To all whom it may concern:

Be it known that I, JOHN H. SPANGLER, a citizen of the United States, residing at Bemidji, in the county of Beltrami and 5 State of Minnesota, have invented certain new and useful Improvements in Collapsible Boxes for Shipment of Eggs and Other Articles; and I do hereby declare the following to be a full, clear, and exact description of the invention, such as will enable others skilled in the art to which it 10 applies to make and use the same.

This invention relates to a collapsible 15 crate adapted for the shipment of eggs and other articles.

It is an object of this invention to provide a collapsible crate or box which can be easily 20 assembled for the shipment of various articles and which can be readily collapsed into a much smaller space for the return of the box to the shipper, thereby effecting a great saving in transportation costs and also a 25 saving of space when the same is stored and not in use.

It is a further object of the invention to 30 provide the folding parts of the crate with inter-engaging and locking device which will hold the same rigidly and securely in packing position.

These and other objects and advantages of 35 the invention will be fully set forth in following description made in connection with the accompanying drawings in which like reference characters refer to the same parts throughout the different views, and in which,

Fig. 1 is a view in side elevation of one 40 side of the box;

Fig. 2 is a view in end elevation thereof;

Fig. 3 is a longitudinal section through 45 the box when in collapsed condition;

Fig. 4 is a transverse section of the box in collapsed condition, the upright or unfolded position of some of the parts being indicated in dotted lines;

Fig. 5 is an isometric view of the inside corner of the box showing the locking device;

Fig. 6 is a horizontal section of one corner 50 of the crate showing the inter-engaging members;

Fig. 7 is a fragmentary section showing locking devices for the crate when in folded position;

Fig. 8 is a section taken on the line 8—8 of Fig. 7;

Fig. 9 is a fragmentary end elevation showing a modified form of the crate;

Fig. 10 is a section on the line 10—10 of Fig. 9;

Fig. 11 is a fragmentary longitudinal section of the box showing a modification; and

Fig. 12 is a section taken on the line 12—12 of Fig. 11.

Referring to the drawings, the crate comprises a base portion 1 shown as having spaced panel forming depressions 1^a extending longitudinally of its bottom surface. This base portion is formed with a fixed up-standing side portion 1^b and an opposite fixed up-standing side portion 1^c of somewhat greater height than the portion 1^b. The base also has a fixed end portion 1^d of considerably greater height than the fixed side portion 1^c. The corners of the base and fixed side and end portions are reinforced by quadrant-shaped metal plates 2.

The ends of the fixed end portions 1^d and also the end of the fixed side portions 1^b and 1^c are formed at their top surfaces as journals or hinge pins and are also formed intermediate their lengths at their top surfaces with hinge pins. Hinged side portions 3 and 4 are hinged to these hinge or pivot pins by strap hinges of thin sheet metal 3^a and 4^a, and hinged end members or panels 5 are hinged to the pivot pins on the fixed end sections by strap hinges 5^a. The strap hinges are fastened to the hinge sections by suitable screws, pins or rivets. The side and end sections as shown in Figs. 1 and 4 are provided with spaced depressions forming panels. A top member or panel 6 is hinged to substantially the middle portion of the side member 4 by triangular-shaped bails 7 made preferably from stiff metal wire. These bails are fastened to the top member by hinged clips 8 of thin sheet metal and their outturned ends are secured to the side members 4 by hinged clips 9 of thin sheet metal. The top member can thus swing relatively to the side member 4, as

shown in Fig. 4. The top member 6 has, adjacent each edge, a hook member 10 fastened to its undersurface, which hook members are, when the case is in collapsed condition, as shown in Fig. 4, adapted to hook over the top edge of the side member 4. The top member 6 is provided adjacent its central portion with bent bail members 11 hinged thereto and adapted, when the case is in collapsed condition, to swing up over the edges of the end members 5, as shown in Fig. 3, to hold the said members in fixed position. A spring catch comprising a plunger member 13 urged upwardly by a spring in a socket adjacent the ends of the members 5, holds the bail members 11 in engaged position. The end members 5 are provided at their side edges with angle members 5^b shown in section in Fig. 6, one side of which angle member extends parallel to and slightly spaced from the inside surface of said end members. The side members 3 and 4 are provided with similar angle members 3^b, one outside surface of which is flush with the end surface of said side members and the other side of which is secured to the inside surface of said side members. When the side and end members are in upright position, the angle members 3^b and 5^b come into frictional engagement as shown in Fig. 6. These angle members thus prevent outward swinging movement of the end and side sections when the same are in upright position. In order to prevent inward swinging movement of these members, locking clips 14 are pivoted at the ends of the side members adjacent the top thereof and swing into slots 15 formed in the end member, as shown in Fig. 5.

When the box is erected for packing condition, the side and end members stand in vertical positions with the members 3^b and 5^b engaged and the locking clips 14 in the position shown in Fig. 5. The top member 6 then extends across the box, the top surface of the same being flush with the top surface of the end members 5, as shown in Fig. 2.

When it is desired to collapse the crate, locking members 14 are disengaged and the side member 3 is then swung down substantially in contact with the base or bottom member 1. The top member is then swung upwardly and outwardly and the hooks 10 engage over the edge of the side member 4 and these members are then swung down together, the side member 4 coming in substantial contact with the side member 3 and the top section 6 being superposed on said side member 4. The end sections are then swung down on top of the top member 6 and the bail member 11 swung up over the edges of the end members. The end members are provided with grooves 5^c to accommodate the sides of the bail members 11 and

the top member 6 is also provided with grooves 6^a to accommodate the transverse portions of the bail members 11 when the same are swung to inoperative position. The bail members 15 form handles for the case and are pivoted to the center of the end sections 5, as shown in Fig. 2.

It is desired to sometimes use the crate as a shipping box without the top member 6. When this is done, the top member will simply be removed with its attaching bail members 7 and the top portions of the end members 5 will then be detached and hinged as portions 16, shown in Figs. 9 and 10. When the box is erected for use, the portion 16 will be swung down at the inside of the end members 5 and will act as a brace for the side portions to prevent their being collapsed inwardly.

It is also contemplated to place a partition member 17 in the box to extend transversely thereof substantially at the central portion. This partition member will be hinged at its bottom and movable into collapsed position, as shown in dotted lines in Fig. 11. Suitable spring actuated catches 18 will be arranged in the sides of the box to hold the partition members in upright position. When this partition member is used the fixed side sections of the box and the fixed end sections will necessarily be somewhat higher so that the side and end sections can fold downwardly onto the partition member.

From the above description it is seen that applicant has provided a simple and efficient crate and one which can be very quickly and easily placed in packing and shipping or in collapsed positions. In the illustrated embodiment of the invention the various sides of the crate are shown as made of wood, but it will be understood that any desired material may be used. The crate has been found to be very successful and efficient in actual use.

It will, of course, be understood that various changes may be made in the form, details and proportions of the device without departing from the scope of applicant's invention, which, generally stated, consists in the matter shown and described and defined in the appended claims.

What is claimed is:

1. A folding crate having a bottom portion, a short fixed side portion rigid therewith, a side portion hinged to said fixed side portion and foldable down flat on said bottom portions, an opposite higher fixed side portion and another side portion hinged thereto and foldable down on said first mentioned hinged side portion, fixed end sections on said bottom member, hinged end sections connected thereto and foldable downward on said last mentioned side portions, and a top member connected by

hinged bails to one of said side portions and foldable down over the same.

2. The structure set forth in claim 1, said bail member being connected adjacent the side edge of said top member and also being connected adjacent the middle portion vertically of said side member.

3. The structure set forth in claim 1, the end sections folding down over the top section, and means on said top section for holding the end sections in folded position.

4. A collapsible crate having a base panel, a foldable side and foldable end panels, a second foldable side panel, a foldable top panel hinged thereto by spaced bail

members, and means on the underside of said top panel to hook over the edge of the side panel to which it is hinged when the crate is in folded position.

5. A crate comprising a base portion, 20 short fixed side and end sections, collapsible side and end sections, hinged at their lower edges to said fixed sections, and pivoted flat locking blades at the ends of the side sections engageable in slits in said end 25 sections, said blades lying substantially flush with said side sections.

In testimony whereof I affix my signature.

JOHN H. SPANGLER.
